UNITED STATES PATENT OFFICE

WILLIAM A. EDWARDS, OF CHICAGO, ILLINOIS

CARBURETING DEVICE

Application filed September 13, 1923. Serial No. 662,584.

The purpose of this invention is to provide an improved construction of fuel feeding device for internal combustion engines, especially adapted for the purpose of causing 5 the fuel mixture and quantity drawn by the engine suction to be automatically more perfectly than heretofore adapted to the requirement of the engine at its different speeds, as when idling and when operating at high 10 speed under load.

In the drawings:

Figure 1 is a diagrammatic elevation for showing the several elements of the mixture in their relative positions and in relation to 15 the float chamber or other constant level device to the main fuel tank.

Figure 2 is a horizontal section, axial with respect to the fuel mixture conduit and liquid fuel ducts and nozzle therein.

20 Figure 3 is a detail elevation showing a modification in respect to the relative positions of two venturis in the fuel mixture conduit and the fuel ducts discharging therein.

This invention is adapted for use in connection with a low level main fuel supply tank, serving to dispense with any additional fuel lifting means, as may be understood from the diagrammatic elevation, Figure 1; but its 25 distinguishing characteristic is independent 30 of the capacity of the device for lifting the fuel; and it may be employed regardless of the function of fuel lifting. The diagrammatic views, however, are designed to illustrate the invention applied under conditions 35 and in a manner to render the apparatus operative as a fuel lifter, independently of its primary function relative to impression.

The first characteristic feature of the invention consists in the provision of means for 40 causing the suction of the engine to operate for drawing the liquid fuel into the fuel mixture conduit through two separate venturis, the venturis being successively positioned in the fuel mixture conduit so that the air drawn 45 in for the fuel mixture traverses both venturis, one after the other, and may take in a charge of fuel at either or both of the venturis from the nozzle discharges in them respectively.

50 A second characteristic feature of the in-

vention is that the conditions at the two venturis affecting the capacity of the air flow for taking liquid fuel from the nozzle are different, so that equal air flow may take unequal quantities of liquid fuel at the two 55 nozzles respectively.

In the drawings A represents a main fuel tank which may be at a low level with respect to the engine intake. B represents a float chamber positioned for being supplied 60 with liquid fuel by gravity from the main tank, A. C is fuel mixture conduit leading to the fuel intake pipe and thence to the engine intake.

From the float chamber, B, liquid fuel is 65 delivered through two pipe branches, D¹ and D², to separate venturis C¹ and C², situated successively in the fuel mixture conduit which has its air intake at C³ where it may be provided with an anterior throttle, E, connected in any usual manner, (not shown), for operation at will or automatically, according to the conditions of service.

The differentiation between the venturis and the relation of the fuel nozzles thereto 70 may be effected by several different means, separately or in conjunction; for it is well understood that the point or area of greatest depression in a venturi through which an air flow is produced, is always somewhat beyond the point of greatest constriction of the venturi and varies in respect to its exact location according to the angle of taper of the venturi passage at the discharge side of the constriction, and according to the velocity of air flow 75 through the venturi throat; and that with a given engine action drawing in a given quantity of air, the velocity at the constriction is proportional to the cross-sectional area 80 at the constriction.

One differentiation is therefore obtained by locating the points of fuel discharge from the nozzles d¹ and d² in the two venturis respectively at points in the respective venturis 85 which are different in relation to the low pressure areas of the venturis at an assumed engine speed. As illustrated in the drawings, the discharge nozzle d¹ of the fuel duct D¹ in the venturi C¹ is located at what is 90 intended to be understood as the point of 95 100

greatest depression in that venturi resulting from a certain assumed velocity of air corresponding to a certain engine speed and throttle opening; and the discharge nozzle 5 d^2 in the venturi C^2 is shown positioned at a more advanced point in the latter venturi. The assumed engine speed and throttle opening which produces the lowest depression in the venturi C^1 at the point of the nozzle d^1 10 will not produce the lowest depression in the venturi C^2 at the point of the nozzle d^2 in that venturi; but a different engine speed and throttle opening which will produce a maximum depression in the venturi C^2 at the 15 point of the nozzle d^2 will not produce the conditions for maximum proportional fuel discharge at the nozzle d^1 in the venturi C^1 . A proper relating to each other of the two 20 venturis and their respective fuel nozzle positions will cause the variation in efficiency of each assembly, of venturi and nozzle to be compensated and complemented by the variation in the opposite direction of the efficiency of the other assembly.

25 In addition to the above described means of differentiating the capacity of equal air flow to produce liquid fuel flow, or instead of these means, such differentiation may be effected by differentiating the contour of the venturis 30 in axial section, as may be seen by comparison of the venturis, C^1 and C^2 , the former being more constricted than the latter.

A third means of differentiation may consist in locating the venturis at different levels 35 with respect to the constant level chamber or float chamber, as seen in Figure 3 in which the two venturis are positioned successively in an upwardly extending portion of the fuel conduit. The venturi, C^2 , which has a larger 40 throat or less constriction, and which has the nozzle at the advanced point, being at a higher level than the venturi, C^1 , so that equal air flow through the two venturis independently of the difference in the proportions 45 of the venturis and the relation of the fuel nozzle thereto, will cause less fuel to be drawn through the venturi, C^2 , than the venturi, C^1 .

50 All of the several means above described of differentiating the two venturis and fuel connections thereto in respect to the capacity of air flow for producing the fuel flow, are exemplified in the construction and arrangement of Figure 3.

55 The reason for and importance of differentiating the means affecting fuel discharge at the two venturis, arises from the fact that with given proportions of venturi and given relation of the fuel discharge to the venturi 60 constriction, up to a certain point the fuel flow, increases with the suction which causes the air flow, and therefore with the engine speed and opening of the throttle. This certain point is that at which the "skin friction" 65 of the air at the venturi throat operates as an

offset, and prevents further increase of fuel flow, or reduces it ultimately to a negligible amount. The less the constriction of the venturi, and the farther advanced the nozzle or fuel discharge mouth is beyond the venturi constriction, the greater may be the air velocity due to the engine speed and throttle opening, without passing the point at which increase of velocity ceases to produce increased fuel flow. If only one fuel discharge 70 is provided at only one venturi, given proportions and relations of the fuel discharge mouth to the venturi throat will be operative for properly proportioning the fuel mixture, only through a limited range of engine speed and throttle opening; but by providing two fuel discharges, differentiated as to capacity of air flow to produce fuel flow, it is possible to so differentiate them that as the air velocity due to engine speed and throttle opening 75 passes beyond the capacity of one of the venturis and fuel nozzle therein to respond proportionately in respect to fuel flow, the stage of responsiveness of the other is reached; with some overlap of the decline of responsiveness of the first and growth of responsiveness of the second; and thus the maintenance of proper proportions of air and fuel in the fuel mixture is effected automatically 80 throughout a wide range of engine speed and throttle opening; and by judicious differentiation of the two fuel discharges the entire range from idling speed of the engine to maximum speed under load, may be covered 85 with proper proportioning of fuel mixture.

90 It may be understood that the parts above described are dimensioned so that the fuel mixture as delivered beyond the second venturi will be too rich for efficiency under conditions of open throttle and consequent high engine speed under load. And under these conditions additional air will be taken into the mixture at an air inlet between the second venturi and the connection with the intake manifold. This may be understood as indicated in Figure 1 by the showing of a fuel mixture conduit, C, discharging in a larger conduit, G, which constitutes the fuel intake 95 connected to the intake manifold of the engine and having a venturi, G^1 , at whose constriction the fuel mixture conduit, C, discharges. And it will be noted that, as shown in this figure, the air inlet between the second venturi and the connection to the manifold, there is provided a venturi, G^1 , through 100 which the fuel mixture conduit, C, discharges, and immediately anterior to which there is provided the air inlet mentioned above as located between the second venturi and the intake manifold connection. At this air inlet there is provided a spring-controlled valve, G^2 , for determining, by the resistance of the spring to the opening of the valve, the stage 105 of suction at which additional air will be admitted. This valve will be opened for ad- 110 115 120 125 130

mitting such additional air proportionally to the excess of the suction above the predetermined degree for which the spring is adjusted.

I claim:—

- 5 1. A carbureting device for internal combustion engine comprising in combination with a fuel source in which the fuel is maintained at a substantially constant level, a fuel mixture conduit having an initial air inlet and comprising two venturis consecutively positioned in the course thereof both antecedent to any outlet or additional air inlet; the discharge mouth of the first venturi being registered with the entrance mouth of the second venturi without material reduction of flow capacity of the passage between the venturi constrictions, means for fuel flow from said source comprising connections for discharge of the liquid fuel in the two venturis respectively, the forms and dimensions of said venturis and the relation thereto of the points of discharge of said fuel connection being different, the differentiation of location of the fuel discharge openings relatively to the constrictions of the respective venturis and the differences in the form and dimensions of said respective venturis operating to cause an increase of the ratio of the fuel flow to the air flow at one of said venturis, due to change of the throttle opening and the engine operation, to be concurrent with the decline of said ratio at the other venturi.
- 10 2. In the construction defined in claim 1, one of said fuel discharge openings being at a higher level than the other.
- 15 3. In the construction defined in claim 1, one of said venturis having its constriction of greater diameter than the other.
- 20 4. In the construction defined in claim 1, the two venturis being at different levels.
- 25 5. In the construction defined in claim 1, the two venturis being at different levels, the one which is at the higher level having its constriction of greater diameter than the other.
- 30 6. In the construction defined in claim 1, the two venturis being of different diameters, and the openings for fuel discharge thereinto being at different levels.
- 35 7. A carbureting device for internal combustion engines comprising in combination with a fuel source in which the fuel is maintained at a substantially constant level, a fuel mixture conduit having an initial air inlet and containing at least two air flow accelerating cross sectional reductions consecutively positioned in the course thereof antecedent to any additional outlet or additional air inlet, whereby the entire air current is delivered
- 40 8. from each preceding to each succeeding cross sectional reduction; means for discharge of the liquid fuel in the conduit proximate to said cross sectional reductions respectively, the dimensions of said cross sectional reductions being different, the differentiation of

location of the fuel discharge openings relatively to the degree of constriction of the respective cross sectional reductions and the differences in the dimensions of said reductions, being calculated and arranged as described for operating to cause an increase of the ratio of the fuel flow to the air flow at one of two consecutive cross sectional reductions due to the change of the throttle opening and engine operation to be concurrent with the decline of said ratio at the other of said consecutive reductions.

In testimony whereof, I have hereunto set my hand at Chicago, Illinois, this 10th day of September, 1923.
